UNITED STATES PATENT OFFICE.

SEIJIRO HOSHIDE, OF SEATTLE, WASHINGTON.

ICE-CREAM-CONE MACHINE.

1,301,697.

Specification of Letters Patent.

Patented Apr. 22, 1919.

Application filed August 22, 1918. Serial No. 250,950.

To all whom it may concern:

Be it known that I, SEIJIRO HOSHIDE, subject of the Emperor of Japan, residing at Seattle, in the county of King and State of Washington, have invented certain new and useful Improvements in Ice-Cream-Cone Machines, of which the following is a specification.

This invention relates to apparatus by which ice-cream cones or the like are formed and cooked.

The object of my invention is the improvement in apparatus of this character to render it more simple and inexpensive in construction and more efficient and economical in operation.

With the foregoing and other objects in view, the invention consists in the novel arrangement and combination of parts hereinafter specifically described, illustrated in the accompanying drawings and pointed out in the appended claims.

In the drawings, Figure 1 is a fragmentary plan view of a machine embodying my invention. Fig. 2 is a side elevational view with parts omitted and showing a mold cover plate in its elevated position. Fig. 3 is a detail sectional view taken substantially through 3—3 of Fig. 1 to illustrate the batter supply appliances. Fig. 4 is a detail sectional view of a pair of gas burner devices. Fig. 5 is a front elevational view of a latch for releasably connecting a pair of mold blocks.

In said drawings, the reference numeral 10 designates an upright tubular post comprising a plurality of pipe elements 10¹, 10², 10³ and 10⁴, the adjacent ones being connected by a T-fitting 11 and coupling elements 12 and 12¹. Said coupling elements are secured in spaced relations by lock nuts 13 and 13¹ engaging screw threads provided in the respective pipes.

Rotatably mounted on the post 10 between the lock nuts 13 is a hub 14 to which are rigidly secured horizontal radially disposed brackets 15 having secured to the outer end of each a rectangular shaped block, such as 16. Hingedly connected by pins 17 to lugs 15¹ provided at the opposite sides of a bracket are arms 18 carrying block elements 19 adapted to be brought into juxtaposition with the side faces 16¹ of the associated block 16 and against which the block elements 19 may be releasably held by

means of a latch 20 connecting the handle bars 18¹ provided on said arms.

The inner and outer blocks 16 and 19 constitute the molds of the apparatus, being formed in their adjacent sides with complementary recesses 21 which, upon being brought together, afford conical cavities in which the cones are shaped.

Provided for the respective mold cavities are conical cores or formers 22 depending from a cover plate 23, one for each set of blocks, said plate being hingedly connected for vertical movements by a pin 24 to the upper end of a swivel bolt 25 which extends through the respective bracket 15. By means of such connections, a cover plate is adapted for both vertical and horizontal swinging movements.

The cover plates are provided with handle arms 26 whereby the movements of the plates relative to the respective molds are conveniently effected.

27 represents a rod connected to a support 28 provided on a cap 28¹ screwed on the upper end of the post pipe-element 10⁴. Said rod extends radially from the post and is provided adjacent to its outer end with a notch 27¹ in which the cover plate handles 26 may be successively engaged for temporarily retaining a cover plate in the elevated position in which it is represented in Fig. 2.

Included in the invention are means for supplying batter to the formers to be conveyed thereby into the molds for cooking. To these ends, a batter reservoir or receptacle 29 (Figs. 1 and 3) located at a higher elevation than the molds, is provided with an outlet spout 29¹ which is controlled by a valve 30 yieldingly held on its seat at the top of said spout by means of a spring 31 interposed between said valve and a guide 32 for the valve stem.

33 represents a dip pan supported upon a tray 34 secured to the upper end of a bar 35 arranged for vertical movements in a hollow standard 36. Said bar is elevated by means of a foot lever 37 fulcrumed at 38 and is lowered by gravity when foot pressure is removed from the lever.

The dip pan 33 is connected by an inclined conduit 33¹ with a cup 39 disposed to receive the spout 29¹ of said reservoir when the cup is raised with the dip pan into the respective positions in which they are represented by full lines in Fig. 3. Said cup 110

also accommodates a flotative body 40 suspended by a cord 41 from a lever 42, fulcrumed at 43 to a support provided on the reservoir, said lever being connected by a 5 cord 44 with the stem 30¹ of the valve 30.

The surfaces of the batter in the dip pan 33 and cup 39 are in the same horizontal plane. The body 40 when floating in the batter exercises no power to open the valve 10 30; but when unsupported, the weight of said body will assert itself to overcome the power of the spring 31 and effect the opening of the valve to supply batter to the cup and communicating dip pan.

15 This will occur when the cup is at its lowermost position, the cord 41 being of sufficient length to accommodate the vertical movements of the cup.

Heat for cooking the batter is applied 20 directly above and below the cover plates and blocks of the respective molds at the positions B, C, D and E, whereat the latter are stopped in their revoluble movements for the purpose of removing from one set of molds, 25 when at station A, the cones cooked therein, and in supplying batter to such set of molds.

For such heating I provide at the referred 30 to stopping positions (B, C, D, E), duplex burners above and below the molds, said burners comprising pairs of parallel horizontally disposed pipe elements 45, 45¹ connected by fittings 46 with pipes 47 which are connected to the non-rotatable couplings 12, 12¹ by being screwed into threaded holes 48 of 35 the same.

Fuel gas is delivered to the interior of post 10 through fitting 11 and pipe 11¹ leading from a source of gas supply. The burner elements 45 and 45¹ above and below the orbital path of the molds are respectively provided in their under and upper sides with orifices through which the gas issues to be consumed in proximity to the several molds when they are at or adjacent to their several 45 stopping positions.

When a mold has completed a cycle of revolution by a series of intermittent movements, it is stopped at A (Fig. 1) and its cover plate 23 is raised to withdraw the 50 formers 22 therefrom from the referred to mold. The cover plate is, preferably, held in such elevated position by engaging its handle 26 in the notch 27¹ of rod 27, as shown in Fig. 2.

55 The latch 20 is then disengaged, whereupon the operator swings outwardly by means of handles 18¹ the arms 18, thereby separating the mold blocks 19 from the block 16. With a mold thus opened, the cones 60 will usually drop out. Should any fail to do so, the operator releases the same by pushing them with his fingers from the part of the mold to which they adhere. The mold parts are then brought into closed relations 65 and fastened by the latch 20.

The operator now disengages the cover plate from rod 27 and swings it laterally into the position denoted by F in Fig. 1, and then lowers it to cause the formers 22 to be partly immersed in the batter contained in 70 pan 33 which has previously been elevated from its dotted line position into its full line position, as shown in Fig. 3.

The cover-plate is then raised by the operator to withdraw the formers from the 75 pan with a charge of batter adhering to each former, and thus supplied the latter are restored to their operative positions in the mold by suitably manipulating the cover plate. With the cover plate in closed position the mold is given a revoluble movement to take it into the B position thereby causing the mold from the E position to be brought into the A position where the cooked cones are removed and charges of batter supplied 80 for the production of cones; and so on, each mold is treated and subjected to a batter-cooking heat.

What I claim, is--

1. In apparatus of the class described, a 90 separable mold, a cover plate therefor, formers carried by said plate, a vertically movable batter-containing pan disposed at one side of the mold, and normally retained at a lower elevation than the latter, pedal-actuated devices for raising said pan, and means for connecting said plate to the mold whereby vertical and lateral horizontal movements are afforded the plate for carrying the formers into operative positions within the mold and 95 into positions whereat said formers will be partially immersed in the batter by the elevation of said pan through the medium of said devices.

2. In apparatus of the class described, a 105 mold having a plurality of molding cavities, said mold consisting of a central block, and a side block hingedly connected at one end by a vertical pivot to each side of the central block for horizontal swinging movement whereby articles cooked within the mold may drop therefrom when said side blocks are swung away from said central block, means for releasably securing said blocks in operative relations, a plurality of 110 formers for the respective mold cavities, a cover plate to which said formers are secured, and means for hingedly connecting said plate to the mold to afford both horizontal and vertical swinging movements to 115 the plate relative to the mold.

3. In apparatus of the class described, a 120 revoluble support, a mold having a plurality of cavities and comprising a central block, and side blocks, said central block being rigidly secured to said support and the side blocks being hingedly connected to the support to close against said central block, formers for the mold cavities, a cover plate carrying said formers, a bolt journaled in said 125 130

support for rotation about a vertical axis, and means to hingedly connect said plate to the bolt about a horizontal axis.

4. In apparatus of the class described, the combination with a separable mold, a cover plate connected thereto for relative vertical and horizontal movements, and formers depending from said plate, of a batter-containing pan, a cup communicatively connected therewith, means to effect coincident vertical movements to said pan and cup, a batter reservoir having a discharge opening, a spring-closing valve for said opening, and means rendered operable to open said valve by the lowering of said pan and cup to replenish the same with batter.

5. In apparatus of the class described, the combination with a post, a hub mounted for rotation on said post, brackets secured to said hub, a mold carried by each of said brackets, one of the parts of each mold being

rigidly secured to the respective bracket, and complementary mold parts hingedly connected for relative horizontal movements to said brackets, of cover plates hingedly connected for both vertical and horizontal movements to the respective brackets, a dipping pan, means to supply batter to said pan, formers depending from said plates and adapted to be carried thereby into position for immersion in the dipping pan or into coöperation with the respective molds, and means to heat the molds at selected positions into which said molds are successively brought by the intermittent rotation of said hub. 25 30 35

Signed at Seattle, Washington, this 8th day of August, 1918.

SEIJIRO HOSHIDE.
